UNITED STATES PATENT OFFICE.

CHARLES H. ALLEN, OF SYRACUSE, NEW YORK.

DESIGN FOR A CASING FOR HAND SPRAYING APPARATUS.

46,157.

Specification for Design.

Patented July 28, 1914.

Application filed April 11, 1913. Serial No. 760,556. Term of patent 14 years.

To all whom it may concern:

Be it known that I, CHARLES H. ALLEN, a citizen of the United States, residing at the city of Syracuse, in the county of Onondaga and State of New York, have invented a new, original, and ornamental Design for a Casing for Hand Spraying Apparatus, of which the following is a specification, reference being had to the accompanying drawing, forming part thereof.

The figure is a side elevation of a casing for hand spraying apparatus, showing my new design.

I claim:

The ornamental design for a casing for hand spraying apparatus as shown.

CHARLES H. ALLEN.

Witnesses:

H. E. CHASE,
EVA E. GREENLEAF.
